UNITED STATES PATENT OFFICE.

WILLIAM MITCHELL, OF NEW YORK, N. Y.

IMPROVED SUGAR-MOLD CARRIAGE.

Specification forming part of Letters Patent No. 44,211, dated September 13, 1864.

To all whom it may concern:

Be it known that I, WILLIAM MITCHELL, of the city, county, and State of New York, have invented a new and Improved Sugar-Mold Carriage; and I do hereby declare that the following is a full, clear, and exact description thereof, which will enable others skilled in the art to make and use the same, reference being had to the accompanying drawings, forming part of this specification, in which—

Figure 1 represents a side sectional view of my invention, taken in the line $\alpha\alpha$, Fig. 2; Fig. 2, a plan or top view of the same; Figs. 3, 4, 5, and 6, plan or top views of the top plates of the same.

Similar letters of reference indicate like parts.

This invention relates to a new and improved carriage for conveying sugar-molds to the drying-rooms in sugar-refineries.

The object of the invention is to obtain a carriage for the purpose specified which will be capable of conveying different-sized molds used in a refinery, and also capable of carrying a greater number of molds than any of the carriages hitherto constructed, and one which may be economically manufactured, and drawn or manipulated with greater facility than usual.

A represents the bottom of the carriage, which may be constructed of plank and mounted on the wheels B B C C. The back wheels, B B, are fitted loosely on an axle, D, which is bolted to the bottom of A. The front wheels, C C, are caster-wheels, and are at the lower ends of rods E E, which pass up through sockets F in the front of the bottom A, and have their upper ends fitted in bearings a, attached to the front cross-piece, b, of the frame of the carriage, the rods E E being allowed to turn freely in the sockets F and bearings a, the front part of A resting or bearing on the upper ends of the forks c of the rods E, in which the caster-wheels C are fitted. (See Fig. 1.)

The framing of the carriage is composed of four cast-iron corner-pieces, G, which are slightly inclined outward, both laterally and longitudinally with the carriage, so as to give the framing a slight flaring form, corresponding to the taper form of the molds. These corner-pieces are of angle form in their hori-

zontal section, and are strengthened by an upright center piece, d, the lower ends of which pass through A, and may have screw-nuts upon them for securing the corner-pieces to A. The upper ends of the corner-pieces at the front and rear of the carriages are connected by cross-pieces b b.

H H' H'' H''' represent the top plates of the carriage. These top plates are of cast-iron, and each are provided with a lip or flange, e, at their ends to fit over the cross-pieces b b. These top plates may be readily taken off and fitted on the cross-pieces of the carriage, and any one of said plates used as may be required. The plate H, Fig. 3, is provided or cast with three semicircular recesses f, at each side, as shown in Fig. 3, said plate holding six molds, I, of the largest size. The plate H', Fig. 4, has four semicircular recesses f at each side to hold eight molds of a smaller size. The plate H'' has five semicircular recesses f at each side, and two rows of circular openings, g, five in each row, to hold twenty molds of a still smaller size, the smallest molds used being held by the plate H''', which has six notches f at each side and three rows of circular openings, h, six openings in each row, to receive in all thirty molds. On the carriage, in Fig. 2, a plate, H^x, is represented with four recesses f at each side, and three circular openings, i, at its center. By this arrangement it will be seen that the carriage is rendered capable of carrying a greater or less number of molds, according to their size, the capacity of the carriage being varied by simply changing the plates, which may be done in a moment of time. The carriages as at present constructed are not capable of being thus varied in capacity, and much time is therefore lost in conveying the molds of smaller size.

By having two caster-wheels at the front part of the carriage, instead of one, as now used, the carriage is better supported, and not liable to sink into the floor, in cracks or crevices, or become impeded, as when one caster-wheel only is used.

I claim as new and desire to secure by Letters Patent—

1. A sugar-mold carriage provided with a series of removable top plates having recesses and openings, either or both, for the purpose

of varying the capacity of the carriage to carry a greater or less number of molds, according to their size, as set forth.

2. The employment or use of two caster-wheels, C C, at the front of the carriage, in connection with the bottom A, corner-pieces G, and cross-pieces b b, all arranged as shown,

to form a new and improved device, for the purpose specified.

WILLIAM MITCHELL.
